UNITED STATES PATENT OFFICE.

VICTOR J. REED, OF ROCKFORD, ILLINOIS.

PORTABLE RUBBING-MACHINE.

1,099,617.

Specification of Letters Patent.

Patented June 9, 1914.

Application filed August 9, 1913. Serial No. 783,656.

To all whom it may concern:

Be it known that I, VICTOR J. REED, a citizen of the United States, residing at Rockford, in the county of Winnebago and State of Illinois, have invented a new and useful Portable Rubbing-Machine, of which the following is a specification, reference being had to the accompanying drawings and to the letters and figures of reference marked thereon.

The invention relates to the type of machine that is controlled by hand and adapted for various rubbing operations, more especially for sand-papering or polishing surfaces of furniture or other articles, the invention having reference more particularly to means for removably connecting sandpaper, rubbing felt or similar devices to the machine.

An object of the invention is to provide an improved portable rubbing machine that shall be so constructed as to be adapted to be operated by various means, as may be, most convenient or desirable in the shop or factory where used.

Another object of the invention is to provide a rubbing machine of improved construction that shall be provided with means for enabling the operator to quickly change the abrading or rubbing devices on the machine, so as to adapt it for different classes of work.

The invention consists in an improved rubbing machine having various novel features of construction, more especially with respect to the reciprocating heads thereof, and gearing for their operation, and also to interchangeable rubbing plates, and to novel means for detachably securing the plates to the heads.

The invention consists also in the novel parts and combinations and arrangements of parts as hereinafter particularly described and further defined in the accompanying claims.

Referring to the drawings, Figure 1 is an end elevation of the improved rubbing machine as preferably constructed; Fig. 2, an inverted plan of the machine; Fig. 3, a vertical longitudinal section on the line A A in Fig. 1; Fig. 4, a fragmentary sectional detail of parts of the improved rubbing machine; Fig. 5, a sectional plan view approximately on the line B B in Fig. 3; Fig. 6, a fragmentary side elevation of the machine; Fig. 7, a fragmentary transverse section ap-

proximately on the line C C in Fig. 3; Fig. 8, a perspective view of one of the interchangeable rubbing plates; and Fig. 9, a perspective view of one of the reciprocating heads inverted.

In the different figures of the drawings, similar reference characters indicate corresponding elements or features of construction herein referred to in detail.

As preferably constructed, the improved rubbing machine comprises a suitable frame 1 adapted to constitute an inclosing housing, the upper middle portion of which is raised as a longitudinal rib and has two transverse openings 2 and 3 therein so that three journal boxes 4, 5 and 6 are formed, the frame being preferably composed of aluminum, and three bushings comprising journal bearings 7, 8 and 9 are inserted in the boxes, respectively. A main shaft 10 is rotatably mounted in the bearings and may extend beyond the frame so that the driving power, such as a flexible shaft or other means, may be connected thereto. Preferably a spur-toothed gear wheel 11 is secured to the shaft in the opening 3 whereby to drive the shaft, and a bevel gear wheel 12 is secured to the shaft in the opening 2 so as to be between the boxes 5 and 6 for transmitting the motion imparted to the shaft. The under side of the top proper of the housing is designed so as to constitute a foundation 13 integrally with the journal box 6, and it is provided with a downwardly extending stub shaft 14 on which is rotatably mounted a bevel gear wheel 15 that is in mesh with the wheel or pinion 12, the wheel 15 being provided with a crank pin 16 whereby to convert rotary motion into reciprocatory motion for operating the reciprocating heads. The under side of the journal box 5 is provided with a foundation plate 17 having a stub shaft 18 thereon that extends downward and preferably has a screw threaded bore in which a screw 19 is removably inserted and provided with a head or collar 20 which is seated against the end of the stub shaft and extends laterally beyond it so as to retain a lever 21 that is rotatably mounted between its ends on the stub shaft, one end portion of the lever being provided with a wrist pin 22. A pitman 23 is connected to the wrist pin and also to the crank pin 16 so that the rotation of the wheel 15 causes oscillation or rocking of the lever, the latter having

also a wrist pin 24 connected thereto in

proximity to the wrist pin 22, the opposite end portion of the lever 21 being provided with a wrist pin 25.

The side portions of the frame 1 are 5 adapted to guide reciprocating heads and preferably are provided with separate guide bars 26 and 27 suitably secured thereto behind which are arranged suitable wearing strips 28 and 29, each strip preferably being 10 L-shaped in cross section and set into suitable recesses in the inner portions of the sides of the frame and so as to present guide faces opposite to the guide bars, whereby to guide two reciprocating heads.

15 Two reciprocating heads 30 and 31 are provided which are substantially alike but arranged in reverse order end to end with their edge portions in sliding arrangement with the guide bars and the wearing strips 20 above described. The heads are provided respectively with arms 32 and 33 assisting to support two wrist pins 34 and 35 that are connected to the heads respectively and to the arms thereon. A pitman 36 is connected 25 to the wrist pins 24 and 34 for moving and controlling the head 30, a pitman 37 being connected with the wrist pins 25 and 35 for operating and controlling the head 31. It will be observed that the lever 21 is supported 30 nearly at the middle of the frame and that the pitman 36 extends from the lever toward one end of the frame while the pitman 37 extends from the lever toward the opposite end of the frame, and therefore, 35 when the lever rotates in one direction the heads are moved away each from the other and when the lever moves in the opposite direction the heads are drawn each toward the other, so that the tendency of the rubbing 40 friction of either rubbing head to move the machine frame is counteracted by the other, the frictional resistance, therefore, being neutralized.

The under side of the reciprocating head 45 30 is provided with transverse tapering jaw bars 38 and 39, the companion head 31 being provided with similar bars 38' and 39', the outer sides of the bars being cut under or inclined, and the bars 38 and 38' are provided 50 respectively with guideways 40 and 40' that are adjacent to the under side of the heads. The reciprocating heads are provided respectively with pivots 41 and 41' to which levers 42 and 42' are connected, locking 55 bars 43 and 43' being connected to the levers by pivots 44 and 44' respectively, the locking bars extending slidingly into, and are movable through, the guideways 40 and 40' respectively for locking the rubbing 60 plates to the reciprocating heads.

A suitable number of novel rubbing plates as 45 and 45' are provided and any two of them may be detachably secured to and used at one and the same time in connection with 65 the two reciprocating heads, the plates be-

ing designed to be interchangeable, and therefore, are substantially alike. The upper side of the plate 45 is provided with two tapering jaw bars 46 and 47, the plate 45' having similar bars 46' and 47' thereon, the 70 inner sides of the bars being cut under or inclined and adapted to slidingly engage the outer sides of the two bars that are on each one of the reciprocating heads, so as to form a dove-tail connection and draw the 75 bars of the plates snugly to the heads. The opposite ends of each plate have bevel faces 48 and 49 respectively on the upper sides thereof against which to secure a sheet of rubbing medium. Each jaw bar 46 and 46' 80 has a recess 50 therein to receive either locking bar 43 or 43' which securely locks the plate to the head. The jaw bars that are on the rubbing plates have each a suitable number of guideways 51 therein adjacent to 85 the upper side or top of the plate. Each rubbing plate is provided with two pivots 52 and 53 to which two levers 54 and 55 are respectively connected, the levers being provided with pivots 56 and 57 to which operating bars 58 and 59 are connected respectively, and arranged so as to extend over the bevel faces 48 and 49 respectively and also through the guideways 51 in the jaw bars. The clamp bars 60 and 61 are 90 secured to the outer ends of the operating bars respectively and so as to extend opposite to the ends of the rubbing plate, the inner edges of the bars preferably having inclined faces 62 and 63 respectively that correspond approximately to the bevel faces 48 and 49 so that when the clamp bars are drawn forcibly against the bevel edges, the inclined faces 62 and 63 are forced slightly 95 up the bevel edges so as to tightly draw 100 sheets of sand-paper or other material on the face of the rubbing plate. The clamp bar 60 preferably is provided with two guide bars 64 and 65 that are slidingly guided in the adjacent jaw bar, the clamp bar 61 being provided with similar guide bars 64' and 65' that are slidingly guided in the adjacent jaw bar. A pair of suitable rubbing sheets 66 and 66', such as sand-paper, felt or other material, are secured to the respective rubbing plates by means of the clamp bars thereon, as seen more clearly in Fig. 3. The frame of the machine is provided with suitable means for carrying and controlling it, and a suitable motor may be 110 provided for operating the mechanism of the machine if desired. Preferably two saddles 67 and 68 are secured upon the top of the frame 1, and a cylindrical housing-like frame member 69 is secured to the saddles 115 and provided with heads 70 and 71 and also with a handle 72 on its top portion, the latter preferably having a removable plug 73 in its end. The heads 70 and 71 are provided with journal boxes 74 and 75 respec- 120

125 130

tively in which a shaft 76 is rotatably mounted, a spur-toothed gear wheel 77 being secured to the shaft. The interior of the frame member is provided with bearings 5 78 and 79 which support a shaft 80 on which is mounted a toothed gear wheel 81 that meshes with the wheel 77 and also with the wheel 11, the latter extending through an aperture 82 in the wall of the member 69, 10 so that power is transmitted from the driving shaft 76 to the main shaft 10. Ample space is provided in the member 69 to receive a motor if desired, which may be connected to the shaft 76. It will be obvious 15 that the rate of speed transmitted from the shaft 76 to the shaft 10 may be reduced by suitable gearing in lieu of the wheels 77 and 81 if desired, as indicated by dotted lines in Figs. 1, 3 and 6. It is obvious also that if 20 the shaft 76 be extended beyond the head 70 it may be driven by means of a flexible shaft or otherwise as may be desired.

It will be understood that the levers on the reciprocating heads and those on the 25 rubbing plates may be variously latched to prevent accidental movement when the machine is in operation.

In practical use suitable coverings 66 and 66' are secured to the rubbing plates, and the 30 machine is manually controlled and shifted about as may be required while the gearing is being operated so as to cause reciprocatory movement of the rubbing plates, relatively broad surfaces being covered thereby 35 so that the work is rapidly accomplished. The action of the gearing and several parts obviously will be understood from the description of the construction and function of the various elements of the machine without further explanations.

Portions of the invention relating to the rubbing plate herein described, but which may not be claimed in this application, forms the subject-matter of a divisional application for Letters Patent, filed November 45 6, 1913, Serial Number 799,600.

Having thus described the invention, what is claimed as new is—

1. A rubbing machine including a main 50 frame, a main shaft rotatably mounted horizontally in the frame, reciprocatory heads mounted in the frame, gearing connecting the heads with the shaft, a hollow frame member fixedly connected to the main frame, 55 a driving shaft rotatably mounted horizontally in the hollow frame member above the main shaft, and gearing connecting the main shaft with the driving shaft.

2. A rubbing machine including a main 60 frame, reciprocatory heads mounted in the frame, a main shaft rotatably mounted horizontally in the frame, gearing operatively connecting the heads with the shaft, two saddles spaced apart and fixed upon the 65 top of the frame, a hollow frame member

fixed upon the two saddles, a driving shaft rotatably mounted horizontally in the hollow frame member above the main shaft, and a plurality of co-operating toothed gear wheels connecting the main shaft with the 70 driving shaft.

3. A rubbing machine including a frame having two parallel guides, two reciprocating heads slidingly guided by the two guides, a rocking lever pivotally connected between 75 its ends with the frame between opposite end portions of the frame, a pitman connected to one end portion of the lever and extending from one side thereof toward one end of the frame and connected to one of the heads, and a pitman connected to the opposite end portion of the lever and extending from the opposite side thereof toward the opposite end of the frame and connected to the remaining one of the heads. 80

4. A rubbing machine including a frame, reciprocating heads movably guided by the frame and having each a pair of jaw bars transversely arranged on the under side thereof, the outer sides of the bars being 90 under-cut and extending along convergent planes, and rubbing plates having each a pair of jaw bars thereon the inner sides of which are under-cut and extend along divergent planes and in clutching connection 95 with the outer sides of the first described jaw bars, the rubbing plates having each a pair of movable clamp bars on opposite end portions thereof.

5. A rubbing machine including a frame, 100 two reciprocating heads mounted in the frame to move each toward or away from the other, each head being provided with jaw bars and a locking bar and also a lever connected to the locking bar, means for 105 moving the heads, and two rubbing plates provided each with two jaw bars for engaging the jaw bars of a head, each plate having a recess to receive the locking bar and provided with two independently movable clamping bars on opposite ends thereof, each clamping bar being provided with an operating lever that is pivoted to the plate. 110

6. In a rubbing machine, the combination with a main frame, a main shaft rotatably mounted horizontally in the frame, a plurality of reciprocating heads mounted in the frame, and gearing connecting the heads with the shaft, of an inclosing frame 115 member fixedly connected to the top of the main frame, a controlling handle fixed on the top of the member, a gear wheel secured to the main shaft, and means mounted in the frame member connected with the gear 120 wheel for rotating the main shaft.

7. In a rubbing machine, the combination of a main frame, a main shaft rotatably mounted in the frame, two reciprocating heads mounted in the frame, two saddles 125

secured upon the frame, a hollow cylindrical frame member secured upon the saddles and having a controlling handle thereon, a gear wheel secured to the main shaft and 5 extending into said member, and a gear wheel rotatably supported in said member in mesh with said first described gear wheel.

8. In a rubbing machine, the combination 10 of a frame having journal boxes therein, a main shaft rotatably mounted in the boxes, a bevel pinion secured to the shaft, a stub shaft secured to the under side of one of the journal boxes, a gear wheel rotatably mounted 15 on the stub shaft in mesh with the pinion and having a crank pin, and a rocking lever mounted on the under side of another one of the journal boxes, with a pitman connected to the crank pin and the lever, two 20 reciprocating heads mounted in the frame, a pitman connected to the lever and one of the heads, and a pitman connected to the lever and the remaining one of the heads.

9. In a rubbing machine, the combination 25 with a main frame, a plurality of reciprocating heads mounted in the main frame, and operating gearing connected with the heads, of a main shaft rotatably mounted in the frame and connected with the gearing, a gear wheel secured to the shaft, an inclosing frame member fixedly connected to the main frame and having a controlling handle thereon, a driving shaft rotatably mounted in the frame member, a gear wheel 30 secured to the main shaft, and an intermediate gear wheel rotatably supported in the frame member in operative connection with said two gear wheels.

10. In a rubbing machine, the combination 40 with a reciprocating head, of a rubbing

plate having two opposite beveled ends, two clamp bars arranged opposite said ends respectively and having each an operating bar and also two guide bars that are movably guided by said plate, the clamp bars 45 having inclined faces presented opposite to said beveled ends respectively, a rubbing sheet on said plate extending over said beveled ends and engaged by said inclined faces, and two levers pivotally connected to 50 said plate and also to the operating bars of said clamp bars respectively.

11. In a rubbing machine, the combination 55 of a frame having journal boxes therein, a main shaft rotatably mounted in the boxes, a plate secured to the under side of one of the journal boxes and having a stub shaft thereon, the stub shaft having a screw-threaded bore therein, a rocking lever mounted on the stub shaft, a screw secured 60 in said bore and having a head thereon seated on the end of the stub shaft and extending under said lever, a pinion secured to the main shaft adjacent to said box, and a gear wheel rotatably mounted on the under side of another one of said boxes in mesh with the pinion and having a crank pin, with a pitman connected to said lever and the crank pin, two reciprocating heads 65 mounted in the frame, a pitman connected 70 to said lever and one of the heads, and a pitman connected also to said lever and the remaining one of the heads.

In testimony whereof, I affix my signature in presence of two witnesses.

VICTOR J. REED.
